UNITED STATES PATENT OFFICE.

HELMUTH W. TOHTZ AND KIRKE L. BONNELL, OF ST. LOUIS, MISSOURI.

REFRIGERATOR.

Application filed March 17, 1926. Serial No. 95,168.

This invention relates to improvements in refrigerators, and more particularly to the use of mechanical refrigeration in a box of any suitable shape. Prior to this invention, 5 boxes of various types such as display cases and storage receptacles have been provided with pipe coils through which a refrigerant is circulated and the coils are usually coated with ice or frost. In these old refrigerators 10 the heat must be transmitted from the air in the box, through the metal pipes and also through the coating around the pipes. The efficiency and the capacity of the system are, therefore, reduced by the elements which 15 separate the refrigerant from the air in the box. Moreover, the circulation of the air depends upon a difference in temperatures, and some of the air in the box must be at a relatively high temperature.

20 One object of the invention is to produce a refrigerator comprising a box of a suitable type preferably adapted for stores or homes, and containing a duct wherein the air contacts directly with the refrigerant, thereby increasing both the efficiency and the 25 capacity of the refrigerator. A further object is to forcibly circulate the air so as to maintain a substantially uniform temperature in various portions of the box.

30 With the foregoing and other objects in view, the invention comprises the novel construction, combination and arrangement of parts hereinafter more specifically described and illustrated in the accompanying drawings, 35 wherein is shown the preferred embodiment of the invention. However, it is to be understood that the invention comprehends changes, variations and modifications which come within the scope of the claims hereunto appended.

In the preferred form of the invention the refrigerant is forcibly projected into a duct within the box, so as to draw the relatively warm air into the duct where it contacts directly with the spray of refrigerant and then passes from the duct to the contents of the box. The refrigerant itself is thus used to forcibly circulate the air in the box. The relatively warm air can be forced downwardly, regardless of its natural tendency to lie above the cold air, and the latter can be forcibly discharged into the upper portion of the box. The apparatus hereafter described includes an air-conductor having an 55 inlet at one end of a box and an outlet at the opposite end, the inlet and outlet being near

the top of the box. The relatively warm air is drawn into the inlet while the cold air is forcibly projected from the outlet. However, owing to the rapid circulation and intense cooling, there is very little difference in the temperatures at the opposite ends of the box.

Fig. I is a vertical section with a diagram showing the delivery of refrigerant to air 60 conductors in two boxes.

Fig. II is a transverse section taken approximately on the line II-II in Fig. I.

Fig. III is an enlarged top view of one of the air conductors.

Fig. IV is an enlarged side elevation, partly in section, illustrating one of the horizontally elongated air conductors, the middle portion of the conductor being broken away.

A designates a long horizontal box in the form of a display case provided with glass panels 1 and closures 1'. The articles to be cooled may be supported on shelves 2 located between the upright end walls of the box. 80 This box has inner and outer wall members with insulating material 3 between them.

B designates horizontally elongated air conductors located adjacent to each other, as shown in Fig. II, and extending approximately from end to end of the box, as shown in Fig. I.

Each air conductor B is in the form of a horizontally elongated U comprising a down-duct 4 at one end of the box having a flaring 90 inlet in the form of a funnel 5 at the top of the box, an up-duct 6 at the other end of the box having a funnel-shaped outlet 7 at the top of the box, and a horizontal duct 8 located at the bottom of the box and connecting said down-duct 4 to said up-duct 6. The ducts 4 and 6 are preferably circular in cross-section, and the duct 8 is flattened as shown in Fig. II. The funnel-shaped members 5 and 7 are preferably turned toward 95 each other.

To illustrate a suitable means to forcibly spray the refrigerant into the air conductors, we have shown a nozzle 9 extending downwardly in each down-duct 4. An approximately conical spray is forcibly projected from each nozzle to draw air through the inlet 5 and into the duct 4, where it contacts with the refrigerant. The force of the spray pushes the air through the ducts 8 and 6 and finally projects it from the outlet 7. The air is thus forced downwardly at one

end of the box, upwardly at the other end, and then discharged in a course extending lengthwise of the box.

The supports 2 for the articles to be cooled are preferably lower than the inlet and outlet members, and these supports are arranged in a plane between said members. The cold air is discharged over the supports 2 and the warmer air is drawn from a zone above said supports. The course of the air currents will depend upon the velocity of the air, but it is obvious that the cold air is well distributed over the box, and that it will tend to force the relatively warm air toward the inlet funnels 5. These funnels preferably extend from one side of the box to the other, as shown in Fig. II, and their upper edges may be in contact with the top wall of the box. The same is true of the outlet funnels 7. The box A' is provided with a suitable support 2' for articles to be cooled. It contains a row of inlet funnels 5' located at the top of the box and extending from side to side of the box. Each funnel 5' is connected to an approximately U-shaped air conductor comprising a down-duct 4' extending downwardly from the funnel and an up-duct 6' having an outlet member 7' at its upper end. Each down-duct 4' contains a nozzle 9' from which a spray of refrigerant is forced downwardly in the duct 4' to draw the relatively warm air from the top of the box, the air being forced downwardly in duct 4' and then upwardly in duct 6' to the outlet 7', where it is discharged in a horizontal course higher than the support 2' for the articles to be cooled.

A single refrigerating machine may be used to provide the refrigerant for a plurality of boxes, and a single pump may be employed to force the refrigerant to the nozzles in each box. This is diagrammatically illustrated in Fig. I, wherein 12 designates a refrigerating machine to maintain a supply of brine in a tank 13. A pipe 14 leads from the brine tank to a pump 15. This apparatus may be mounted on a basement floor 16 while the boxes A and A' are located on a higher floor 17. The pump 15 is provided with a discharge pipe 18 having branches leading to the several nozzles 9 and 9'. Valves 19 are located in the branches near the pipe 18 to regulate the delivery to the different boxes.

To provide for the return of brine to the tank 13, a return pipe 20 extends from the lower portion of air conductor B to a pipe 21 leading to the tank 13. The air conductors in the box A' are provided at their lower ends with brine pipes 22 leading to an inclined trough 23, and a return pipe 24

extends from the lower end of trough 23 to the pipe 21. The brine can be thus returned by gravity from the boxes to the brine tank.

We claim:

1. A refrigerator comprising a horizontally elongated box, a support for the articles to be cooled located between the end portions of said box, an air conductor in the form of a horizontally elongated U comprising a down-duct at one end of the box having an inlet at the top of the box, an up-duct at the other end having an outlet at the top of the box and a horizontal duct located at the bottom of the box and connecting said down-duct to said up-duct, a nozzle extending downwardly in said down-duct, a refrigerant-container, a pump whereby the refrigerant is forced through said nozzle and projected downwardly in said down-duct to forcibly circulate air from said inlet to said outlet, the outlet end of said up-duct being turned toward the inlet of said down-duct so as to discharge cold air toward said inlet, and means whereby the refrigerant is returned from said air conductor to said refrigerant-container.

2. A refrigerator comprising a horizontally elongated box with a support for the articles to be cooled located between the end portions of said box, and an air conductor in the form of a horizontally elongated U comprising a down duct having a funnel shaped inlet near the top of one end of the box, and an up duct having a funnel shaped outlet near the top of the other end, said funnel shaped members being turned toward each other, a nozzle in said conductor, and means whereby refrigerant is forcibly projected from said nozzle to force the air through said ducts.

3. A refrigerator comprising a box having oppositely disposed walls and provided with a support for the articles to be cooled; and cooling means adapted to forcibly circulate air in said box, said cooling means consisting of an approximately U-shaped air conductor having a down duct with an air inlet near the top of one of said walls, an up duct with an air outlet near the top of the other wall, a connecting duct extending from said down duct to said up duct, the outlet of said up duct being turned toward the inlet of said down duct, a nozzle in said conductor, and means whereby refrigerant is forcibly projected from said nozzle to force air through said ducts.

In testimony that we claim the foregoing we hereunto affix our signatures.
